UNITED STATES PATENT OFFICE.

HERMAN G. PAPE, OF NEW YORK, N. Y.

SOUND-REPRODUCING APPLIANCE.

1,267,587.

Specification of Letters Patent.

Patented May 28, 1918.

Application filed February 28, 1916. Serial No. 80,874.

To all whom it may concern:

Be it known that I, HERMAN G. PAPE, a citizen of the United States, and resident of New York, in the county of New York and State of New York, have invented certain new and useful Sound-Reproducing Appliances, of which the following is a specification.

My invention relates to sound reproducing appliances, and various features of the invention relate more particularly to improvements in telephone receivers.

An object of the invention is to provide a sound reproducer of compact structure in which the sounds are clearly and accurately reproduced, and in which every compression, reflection, refraction, concentration and swelling of sound and air are properly accounted for and the sounds reproduced in the desired strength and in the most natural manner.

A further object of the invention is to provide in a sound reproducing or receiving instrument, an ear piece having such contour as to satisfactorily meet acoustical requirements, and which moreover is adapted to the physiological requirements of the user's ear and is formed to comfortably fit ears of various forms and sizes. The ear piece is designed to be held firmly to the ear while in use, so that exterior or surrounding noises are prevented from interfering. This further makes possible definite instructions for its method of use for the attainment of definite and satisfactory results, which has not been possible with the ear caps heretofore in common use so far as applicant is aware.

As is well known, the users of telephone hand receivers, without this improvement have been obliged to experiment in their method of holding the receiver to the ear, so as to avoid the strains from pneumatic concussions, and secure the best results. On the other hand, the central office operators that use the head receivers have been forced to use the receiver firmly pressed by a band to the ear and thus endure such strains, which is not only a physical strain to the operators, but makes it impossible for them to deliver good and efficient service at all times.

Various other features and advantages of the invention will appear hereinafter.

55 Certain features herein shown are also

disclosed in my copending application Serial No. 874,234, filed Nov. 27, 1914.

Referring to the accompanying drawings, Figure 1 is a sectional view of a sound reproducing instrument constructed in accordance with the principles of my invention. Fig. 2 is a front face view of the same. Fig. 3 is a part sectional view of a different form of receiver. Fig. 4 is a fragmentary sectional view taken at the line 4 of Fig. 1, showing the rounded form of the kerfs in the face of the ear cap.

Referring particularly to Figs. 1 and 2, the telephone receiver comprises a casing including a body portion 5 in which may be mounted the usual electro-magnet and other parts of the sound reproducing mechanism. A cap or ear piece 6 has a screw threaded connection 7 with the part 5 and also serves to clamp in position the diaphragm 8. The cap 6 is so formed that its greatest diameter which is at the point 9 is located some distance forward of the diaphragm. From this point 9, the surface 10 of the cap inclines inwardly and rearwardly at such an angle that the portion of the surface 10 opposite the screw threads 7 is held well away from the table or support on which the receiver rests when laid on such support, as shown in Fig. 3. The purpose of this confirmation of the cap is to protect it from receiving knocks or blows on the rearwardly projecting annular flange portion 11 surrounding the body 5 of the casing. This flange 11 cannot resist without breaking a knock or blow which could be applied at the point 9 without injury to the cap. Stated another way, the tapered form of the cap brings the periphery thereof, at its greatest diameter, opposite the solid front wall or body of the cap. The receiver can therefore readily withstand the hard knocks to which it may be subjected without the need of unduly increasing the thickness of the rim 11, because such rim which is comparatively weak opposite the threads 7 is inclined and carried well away from the table line and thus fully protected.

The cap 6 is provided with an annular series of integral bosses 12 surrounding the cap at its line of greatest diameter, such bosses serving to prevent the receiver from rolling when lying on a table or other support. These bosses may be of such thickness and so spaced that the receiver when lying on a flat table is supported by two of said 110

bosses, the body of the cap being held a slight distance from the table as indicated in Fig 3. The thickness however of these projections 12, as well as the distance between them, may be varied.

- 5 The provision of means to prevent the receiver from rolling not only serves to protect it from accidents by preventing it from rolling off the support on which it may be laid, but has the following further advantage. Receivers which are liable to roll are frequently set on end with the face of the ear cap resting on the desk or support. The latter is often covered with dust, which is thereby collected on the receiver cap and carried to the ear. This unsanitary procedure is practically prevented by the provision of the knobs 12 which remove any occasion for standing the receiver on end.
- 10 The knobs 12 are preferably rounded to prevent them from scratching or marring the furniture with which they come in contact. They do not add to the number of parts of a hand receiver, do not interfere 15 with its symmetrical lines, and being formed on the cap are applicable to any receiver on the market using a separable ear cap.

20 The ear-piece 6 is formed with an inner surface 13 which extends in a continuous curve from the central opening 14 toward the rim of the diaphragm. That is to say, a radial section of the cap as shown in Fig. 1, presents a convex surface line 13 facing the diaphragm. The inner surface of the 25 cap is quite close to and nearly parallel with the diaphragm near the periphery thereof, but curves away from the diaphragm toward the central opening 14, the curvature being much more decided near said opening.

30 It will be seen that there is provided between the diaphragm and the inner surface 13 of the cap, a sound chamber 15. The sound vibrations set up by the diaphragm in the chamber 15 are reflected by the convex surface 13 toward the central opening 35 40 45 14 through which they are directed to the ear.

A feature of my invention is the provision in sound reproducers of compact construction of means for obtaining the proper 50 swelling or retransformation of the sounds produced, so that these are produced in as natural, clear and lifelike a manner as possible. This I have accomplished by providing an annular hollow or groove 16 adjacent to the diaphragm seat on the inside of the cap or wall, which is the place where the sounds emitted from the diaphragm are faintest. This arrangement and method of 55 60 65 supplying capacity therefore does not interfere with the proper concentration of all the vital sounds produced by the vibration of the diaphragm. The capacity provided by the chamber 16 has the effect of absorbing the shock or impact of sound waves

produced by sharp or violent impulses of the diaphragm, providing an elasticity, which has an analogy to that of mechanical shock absorbers, such as found, for example, on automobiles.

70

The capacity provided by the chamber 16, has the effect of absorbing the shock or impact of sound waves produced by sharp or violent impulses of the diaphragm, providing an elasticity which has an analogy to that of mechanical shock absorbers, which are found for example on automobiles; besides this, the capacity chamber also serves to reduce the tone of the speaker's voice to a lower pitch, depending on the depth or capacity of the groove. This is a desirable feature as it rectifies in a measure, the high pitch produced by transmitters of the present day through the tightening of nuts or screws on the microphone mechanism, which 80 distorts it and raises the pitch of the voice, the same as an increased tension on a piano wire raises its pitch. The lowered tone of the speaker's voice invokes a reply in a low tone, thus tending to abate the habit of shouting while telephoning.

85

85 It will be understood that the specific form of the groove or capacity chamber may be materially modified, and such modifications where effective for producing capacity, 90 without materially decreasing the efficiency or concentrating powers of the sound chamber 15, as by the widening of the groove, or by cutting away or destroying too much of the contour line 13, are to be considered 95 within the scope of my invention.

100

The outer face of the cap 6 comprises a curved surface 17 extending from the central opening 14 to the peripheral portion of the cap. A radial section of the cap (Fig. 1) shows this surface to extend in a continuous convex curve from the opening 14. The two surfaces 13 and 17 meet at the opening 14 in substantially a hair line forming the periphery of said opening. The surface 17 110 forms the wall of an outer chamber of considerable depth, formed to fit any ear.

105

The outer surface 17 is provided with radial kerfs or grooves 18 which, when the cap is held snugly against the ear, maintain 115 communication between the outside air and the otherwise closed sound chambers within the cap. These kerfs thus prevent or dissipate the pressure waves or variations in the air pressure due to the vibration of the diaphragm, which pressure waves are, without the provision of the kerfs, focused on the ear drum, causing the sounds to be muffled or indistinct, and also placing a great strain 120 on the ear drum.

125

The utility and practical necessity of these vents on the receiver will be more fully appreciated when their function and operation are considered and compared with those of the vents of one kind or another, which are 130

provided in the transmitters of practically all of the millions of telephones now in the field. These vents are generally found on the mouth pieces of the transmitters, (as shown for example in my Patent No. 822,470) and serve to protect the transmitter membrane against undue concussions so as not to increase or hasten the packing of the microphone, or otherwise derange the adjustment of the instrument. The provision of the vents in the receiver, as herein disclosed, serves in a similar manner to protect the ears of the users against injurious concussions, which is of greater importance (to the public at least, if not to the telephone companies) than the protection of the transmitters.

Incidentally the vents in the transmitters prevent the sounds from becoming muffled, choked and distorted, when the mouth is placed too close to the mouth-piece, or the party speaks too loudly. Such prevention at the transmitter is of minor importance when the sounds are reproduced in the usual receiver and are muffled and rendered indistinct by the receiver being held to the ear. The present invention not only prevents muffling of the sounds that are reproduced by the receiver diaphragm and sent through the ear cap thereof into the ear, but lends utility to that feature of the transmitter whereby is prevented muffling of the sounds that are sent from the speaker's mouth through the mouth-piece of the transmitter into the instrument.

The kerfs 18 are rounded in cross section, as clearly shown in the enlarged detail view, Fig. 4, which conformation is a substantial improvement on the construction disclosed in my Patent No. 800,675, above referred to. I have proved in practice that when the edges of the kerfs are sharp, as shown in said patent, they produce very sore ears, particularly in cases where the receiver is in almost constant use, or used at frequent intervals, and when the receiver is quickly placed to the ear with more or less of a rub. Further, in cases where the cap was constructed with the outer sound chamber shallow, the extension of the kerfs right up to the central opening of the cap caused the sharp edges of the kerfs, when the cap was held against the ear, to be brought against the tragus and antitragus, *i. e.*, the cartilaginous projections immediately anterior and posterior to the meatus auditorius externus, or external opening of the ear. The pressure of the cap, and particularly the sharp edges of the kerfs, and the corners produced at the termination of the kerfs in the central opening of the cap, against these protruding portions of the ear was more or less painful, and caused inflammation and soreness.

65 In the case of operators' head receivers,

the importance of having the kerfs rounded, will be appreciated when it is considered that the head receivers at present in common use, even without the kerfs, produce irritation and soreness of the ear, often causing the operators to resort to the use of handkerchiefs, etc., placed between the ear cap and the ear, or other expedients to relieve the ear from pressure of the instrument thereagainst. Moreover, the manufacture, 70 molding and polishing of the caps was rendered difficult by the sharp edged kerfs extending inward to the central opening of the cap, and involved more careful labor. Also the caps were frequently marred or 80 spoiled through chipping, particularly where the kerfs terminate at the central opening of the cap.

The above objections are overcome in the present invention, wherein the kerfs have 85 a rounded contour and terminate or merge into the outer surface 17 of the cap at a substantial distance from the central opening 14. The rounded contour of the wall 17 provides an outer chamber in the cap of 90 ample depth to accommodate the central protruding portions of the ear, so that they bear lightly, if at all, against the smooth surface 17, and beyond the range of the kerfs 18. The depth of said outer chamber 95 renders it unnecessary to extend the kerfs to the central opening 14. This results in the further advantage that the inner and outer surfaces 13 and 17 may be molded or shaped to meet in a hair line at the opening 14, resulting in a higher efficiency than can be obtained when the wall of the opening itself is of substantial depth.

From a hygienic viewpoint, it will be noted that the kerfs may be readily kept 105 clean, being easily wiped with a cloth as they are rounded throughout their length, and merge into the surface 17. The outer convex surface 17 of the cap with its long easy curvature, is well adapted to fit the human 110 ear, whether large or small.

Means for modifying the vibration of the diaphragm, and thus modifying and controlling the sounds produced thereby, comprises a spring actuated buffer or pressure 115 device. This device may comprise a washer or disk 22 held against the inner face of the diaphragm by a spring 21 attached to said disk. The spring is connected to a screw 20, threaded through the wall of the 120 casing, and adjustable by means of a head 23. The disk 22 is arranged to apply pressure on the inner face of the diaphragm so that the latter will be forced outwardly rather than inwardly, to thereby avoid any liability of the diaphragm striking against the actuating means, such as the magnet, 125 within the casing, which means (not shown) may be the same as disclosed in the Patent No. 800,675, before referred to. The part 22 130

which bears against the diaphragm may be made of cork, felt, or other suitable material to prevent scratching or noisy contact. By adjusting the screw 20, the pressure on the diaphragm may be quickly regulated to secure audibility and purity of tone, and to vary the loudness as may be desired.

It will be noted that the cap of the sound reproducer as herein disclosed may be used 10 as an ear cap for telephone receivers already in common use. As a separate article of manufacture, the cap presents features of great value.

I find that this cap when attached to an 15 ordinary telephone receiver, will eliminate harshness and unnatural bony noises, because it produces the proper swelling and the proper concentration of the sounds, and also because the undesirable interfering echoes 20 are prevented from being retarded in the cap. Familiar voices are distinguished at once and the words, articulations, enunciations, modulations and tone expressions of all voices are faithfully reproduced at their 25 true and intended value, and are heard even by those quite deaf and without ear-drums. Seldom does one have to request for matters to be repeated, while the outer convex line 30 concavity of the cap provides a contour which fits almost every ear.

In the use of the telephone receiver, the manner in which the sound waves that are emitted by the diaphragm act, and the 35 functions of the various parts herein presented, may be summed up as follows:—

Sounds emitted by the diaphragm are sent into the central sound chamber 15 of the cap, where by the aid of the capacity hollow or groove 16, fullness of tone is added to them and, owing to the continuously 40 convex surface 13 the sounds are concentrated and directed to and through the central opening 14. From this point the sounds strike straight into the ear, against which 45 is firmly held the outside surface 17 of the cap, provided with the kerfs 18 to prevent air tight inclosure and permit radial disbursement of surplus pressures.

As the sounds enter the outer canal of the 50 ear they pass freely on into the inner hearing organs, the air pressure which would otherwise be produced within the ear canal being dissipated through the open kerfs.

Thus every intensity, reflection, refraction 55 and compression of sound and air, have in the present invention been properly accounted for, and mark it a distinct triumph over previous methods, so far as applicant is aware because nature's hygienic and 60 physiological laws pertaining to the ear are maintained throughout, with the receiver held firmly to the ear as it should be.

The feature of the capacity groove 16 is particularly desirable on excess voltage systems of telephony; excess voltage being 65

common on any of the present day central battery systems. Otherwise I consider the interior contour of reproducer complete without this feature.

I find that the sound waves as produced 70 by a telephone receiver and transmitted through a cap constructed in accordance with the principles of the present invention, produce exquisite comforts and exhilarating effects, particularly to persons affected with 75 catarrhal or similar middle ear deafness, as they act like a tonic, because they produce a vascular vibration, the result of which is a proper circulation of blood to the parts and the maintenance or rebuilding of a 80 healthy hearing sense. Ear-fatiguing and that trying, straining, nerve and health wrecking or aggravating condition induced by the use of the ordinary telephone receiver ear piece not possessing the improvements here set forth, are avoided by the use 85 of this cap.

I wish not to be limited to the exact construction shown, as modifications may be resorted to without departing from the 90 spirit and scope of my invention.

What I claim is:—

1. In a sound reproducing instrument, a wall provided with an annular seat for the periphery of a diaphragm, said wall having 95 a central opening, the interior surface of said wall being of radially convex sound concentrating contour between said seat and said opening and curving away from said diaphragm seat toward said opening, the 100 curvature of said sound concentrating surface increasing toward said central opening, said wall being provided with a constantly full open groove or capacity chamber between the diaphragm seat and said 105 opening, said chamber providing a means to swell or retransform the reproduced sounds in a location directly adjacent to the diaphragm seat, said radially convex sound concentrating surface being preferably only 110 a hair line distance from the diaphragm adjacent to the groove or chamber.

2. In a sound reproducing instrument, a wall providing an annular seat for the periphery of a diaphragm, said wall having 115 a central opening, the surface of the wall between said seat and said opening constituting an inverted trumpet bell, or a radially convex sound concentrating surface, said surface curving away from the dia- 120 phragm seat toward said opening, the curvature increasing toward said opening, said wall formed with a constantly full open fixed groove or chamber facing the dia- 125 phragm and providing capacity to permit the swelling or retransformation of harsh sounds, said hollow or chamber being located directly adjacent to said seat and between the same and the central opening.

3. A sound reproducing instrument as de- 130

fined in claim 2, and having an exterior trumpet bell with an interior convex line sound projecting or sound swelling contour merging into the sound concentrating 5 surface of the interior inverted trumpet bell contour.

Signed at New York, in the county of

New York and State of New York, this 25th day of February, A. D. 1916.
